(57) **CLAIM**

The ornamental design for a shaped spindle of a door handle for operating a door lock box, as shown and described.

DESCRIPTION

FIG. 1 is a perspective view of a shaped spindle of a door handle for operating a door lock box showing my new design; FIG. 2 is a left side elevation view thereof; FIG. 3 is a right side elevation view thereof; FIG. 4 is a rear elevation view thereof; and, FIG. 5 is a top plan view thereof.

The broken lines illustrate the unclaimed portions of the design and form no part of a claimed design. The spindle in FIGS. 2-5 and the lock box in FIG. 1 are shown separately for clarity of illustration.
